UNITED STATES PATENT OFFICE.

WILLIAM MEREDITH, OF HUNTINGTON BEACH, CALIFORNIA, ASSIGNOR OF ONE-THIRD TO V. W. BAILEY, OF PASADENA, CALIFORNIA, AND ONE-THIRD TO W. H. TAYLOR, OF SOUTH PASADENA, CALIFORNIA.

ROTARY UNDERREAMER.

Application filed April 14, 1924. Serial No. 706,342.

To all whom it may concern:

Be it known that I, WILLIAM MEREDITH, a citizen of the United States, and resident of Huntington Beach, in the county of Orange, State of California, have invented new and useful Improvements in a Rotary Underreamer, of which the following is a specification.

This invention relates to an underreamer 10 having cutters which may be expanded into cutting position after the underreamer has been lowered into the hole.

The objects of this invention are first, to provide an underreamer having cutters, 15 which are mounted to be moved into expanded position at the will of the operator by rotation of the drill pipe; second, to provide an underreamer of the character described which is self contained and requires 20 no auxiliary control devices leading from the underreamer to the surface of the ground for manipulation by the operator; and third, to provide details of construction to insure ease of operation, simplicity, 25 strength, and durability of structure.

These objects together with other objects and corresponding accomplishments are obtained by means of the embodiment of my 30 invention illustrated in the accompanying drawing, in which:

Fig. 1 is an axial section partly in elevation showing the underreamer in contracted position; Fig. 2 is an axial section of the underreamer in expanded position; Fig. 3 is a fragmentary view partly in side elevation and partly in section as seen looking in the direction of the arrows 3-3 of Fig. 1; Fig. 4 is a section as seen on the line 4-4 of Fig. 1, the view being on an enlarged scale; Fig. 5 is a section as seen on the line 5-5 of Fig. 1; Fig. 6 is a section as seen on the line 6-6 of Fig. 1; and Fig. 7 is a section as seen on the line 7-7 of Fig. 1.

Referring more particularly to Fig. 1, the dot and dash lines indicate the box of a tool joint disposed in a string of drill pipe. The underreamer has a body 8 provided with a threaded pin at the upper end 45 for insertion in the box of the tool joint.

The body has a cylindrical head flattened on opposite sides to provide a wrench hold as indicated by 9. The body is formed with

diametrically opposite recesses 10 having their bottom walls converging toward the bottom of the body and forming ways undercut at the sides to receive carriages in which the cutters are mounted. The lower end of the body is reduced in diameter and externally threaded as indicated by 11. Extending axially of the body is a circulation passage 12.

Mounted upon the ways on the body are carriages 14. Mounted in the carriages and extending longitudinally thereof are pintles 15. Journalled upon the pintles are rotary cutters 16. In the present instance, the cutters each consist of two rollers. A pair of spaced ears are provided at the lower end of each carriage as indicated by 17 and journalled therein by means of pins are arms 18. A block 19 is pivotally secured to the lower end of arm 18. Secured to the bottom of the body 8 and upon the threaded portion 11 is a cage 20. This cage has a barrel upper portion, in the bore of which is mounted the block 19. The lower end 21 is flattened at the sides to provide wrench holds and is provided with a threaded bore 22.

Swivelled in the block 19 is a stem 23 having a fast thread. This stem is provided with a circulation passage so positioned that when the stem abuts the lower end of the body, as shown in Fig. 2, a continuous passage is formed. Secured to the end of the stem 23 against rotation is a box 24 for a tapered pin 25 of the tool joint type. The pin 25 is formed on a fish tail bit 26.

When the underreamer is lowered into the hole, it is in contracted position as shown in Fig. 1. When the tool has reached the place where it is desired to cut, the drill stem is rotated in such a manner and stopped so as to cause the cage 20 to ride downwardly upon stem 23 due to inertia. This moves the block 19 upwardly and with it the arms 18 and carriages 14. This movement causes the carriages and cutters to be moved away from one another as shown in Fig. 2. In such position the cutters are expanded so as to engage the walls of the hole and rotation will underream a hole as desired. When it is wished to pull the tool it is elevated and rotated in the opposite direc-

tion, the inertia of the parts is such as to cause the stem 23 to unscrew itself and ride downwardly in the cage.

What I claim is:

1. In a device of the character described, the combination of a body adapted to be secured to a rotatable stem, carriages mounted upon the sides of said body so as to be moved laterally with respect to the axis thereof, cutters mounted on said carriages, a control member rotatably secured to said body, and linkage connecting said carriages and said member whereby rotation of the latter will move said carriages.

2. In a rotary underreamer, the combination of a body adapted to be secured to a drill pipe, carriages mounted upon the sides of said body so as to be moved laterally with respect to the axis thereof, cutters mounted on said carriages, a control member having a stem threadedly engaged with said body whereby rotation of said control member will move said stem longitudinally of said body, and linkage connecting said carriages and said stem whereby to move said carriage.

3. A rotary underreamer, a combination of a body adapted to be secured to a drill pipe, said body being provided with ways at the sides thereof, diverging from the axis, carriages mounted in said ways so that movement of said carriages in said ways will be both longitudinal and lateral to the axis of said body, a control member rotatably secured to said body, and linkage connecting said carriages and said member whereby rotation of the latter will move said carriages.

4. In a rotary underreamer, the combination of a body adapted to be secured to a drill pipe, said body being provided with ways at the sides thereof diverging from the axis, carriages mounted in said ways so that movement of said carriage in said

ways will be both longitudinal and lateral, 45 a control member having a stem threadedly engaged with said body whereby rotation of said control member will move said stem longitudinally of said body, and linkage connecting said carriages and said member whereby rotation of the latter will move 50 said carriages.

5. In a rotary underreamer, the combination of a body adapted to be secured to a drill pipe, said body being provided with 55 ways at the sides thereof diverging from the axis, carriages mounted in said ways so that movement of said carriages in said ways will be both longitudinal and lateral, cutters mounted on said carriages, a control member 60 having a stem threadedly engaged with said body, whereby rotation of said control member will move said stem longitudinally of said body, arms pivotally connecting said carriages and said stem to provide a linkage 65 whereby rotation of said stem will move said carriage.

6. In a rotary underreamer, the combination of a body adapted to be secured to a drill pipe, said body being provided with 70 ways at the sides thereof diverging from the axis, carriages mounted in said ways so that movement of said carriages will be both longitudinal and lateral, rotary cutters mounted on said carriages, a cage secured to the lower end of said body, a control member having a stem threadedly engaged with said cage whereby rotation of 75 said control member will move said stem longitudinally of said body, a block swivelled to the end of said stem within said cage, and arms pivotally connected to said block 80 and said carriages.

In witness that I claim the foregoing I have hereunto subscribed my name this 10th 85 day of March, 1924.

WILLIAM MEREDITH.
